US0D1045717S

(12) **United States Design Patent** (10) Patent No.: **US D1,045,717 S**
(45) Date of Patent: ** Oct. 8, 2024

(54) **HOOD PANEL FOR VEHICLES**

(71) Applicants: **Hyundai Motor Company**, Seoul (KR); **Kia Corporation**, Seoul (KR)

(72) Inventors: **Jung-Hun Park**, Incheon (KR); **Hong-Seok Choi**, Gyeonggi-do (KR)

(73) Assignees: **Hyundai Motor Company**, Seoul (KR); **Kia Corporation**, Seoul (KR)

(**) Term: **15 Years**

(21) Appl. No.: **29/888,793**

(22) Filed: **Apr. 5, 2023**

(30) **Foreign Application Priority Data**

Nov. 14, 2022 (KR) 30-2022-0046900

(51) **LOC (14) Cl.** **12-08**
